CLAIM

The ornamental design for a ceiling fan blade iron, as shown and described.

DESCRIPTION

FIG. 1 is a bottom perspective view of a ceiling fan blade iron shown in the environment of a ceiling fan, showing my new design;

FIG. 2 is a top perspective view thereof;

FIG. 3 is a top view thereof;

FIG. 4 is a bottom view thereof;

FIG. 5 is a right side view thereof;

FIG. 6 is a rear side view thereof;

FIG. 7 is a left side view thereof; and,

FIG. 8 is a front side view thereof.

Portions of the ceiling fan blade iron and the ceiling fan environment are shown in broken lines. Portions shown in broken lines form no part of the claimed design.

1 Claim, 8 Drawing Sheets(56)
